PNEUMATIC THREAD CONTROL FOR LOOMS

Richard G. Turner, Worcester, Mass., assignor to
 Crompton & Knowles Loom Works, Worcester,
 Mass., a corporation of Massachusetts

Application May 4, 1946, Serial No. 687,411

19 Claims. (Cl. 139—256)

1

This invention relates to improvements in thread control mechanisms for weft replenishing looms and it is the general object of the invention to provide effective means for removing the threads of both the outgoing and the incoming bobbins incident to a weft replenishing operation.

When a bobbin is discharged from a shuttle in a weft replenishing loom it leaves a thread which extends from the shuttle to the adjacent selvage. In certain types of replenishing looms, such as those employing a stationary magazine, it has been customary in the past to employ thread cutter mechanism for this thread. The cutter mechanism has ordinarily been located between the magazine and the selvage, and operates on a replenishing beat of the loom to cut the thread into two parts one of which leads to the shuttle and is removed by the outgoing bobbin, and the other part of which extends to the selvage. It has been customary in the past to hold this second part of the thread by clamp mechanism which releases it at the next transfer, at which time the thread may fall on the lay and be drawn into the warp shed.

It is an important object of my present invention to provide pneumatic thread removing means for this second part of the thread of the outgoing bobbin to prevent it from falling onto the lay when it is released by the clamp. To this end I provide a pneumatic tube which reciprocates below the thread cutter and clamp and has an intake mouth to receive the lower end of the thread after it has been cut at the selvage. Since the upper end of the thread is clamped the reciprocating pneumatic remover has several picks in which to attract the lower end of the thread before its upper end is released. It will thus be seen that the clamping of the thread subsequent to selvage cutting materially facilitates entry of the thread into the pneumatic remover. In the sequence or order of operations performed on this part of the thread of the outgoing bobbin it is first cut and clamped, then cut at the selvage, then drawn into the pneumatic remover while still clamped, and thereafter released by the clamp so that it can be removed by pneumatic suction.

The thread of the incoming bobbin is ordinarily held at its outer end by some form of thread holder which in the present instance is preferably pneumatic. On the first beatup of the lay after transfer this incoming thread is moved to the fell of the cloth and becomes attached to the selvage. As the cloth moves progressively

2

forwardly this thread comes into the range of operation of the selvage cutter. In some looms this incoming thread is of considerable length and the thread holder is not always able effectively to remove it from the loom subsequent to cutting at the selvage.

It is another important object of my present invention to provide means by which that end of the incoming thread adjacent to the selvage may be drawn into the aforesaid pneumatic thread remover and then be cut so that one part of it is attracted by the remover and the other part is removed by the thread holder. The means for accomplishing this result includes an auxiliary cutter blade under which the thread is moved on the first beatup after transfer. Subsequently the thread is cut by the selvage cutter and then falls to be attracted by the pneumatic thread remover under the cutter and clamp. At some later time in the operation of the loom subsequent to entry of the incoming thread into the pneumatic thread remover another weft replenishing operation will occur, at which time the incoming thread is cut by the auxiliary cutter and is drawn into the remover. The other part of the thread is removed by the pneumatic thread holder.

The operation of the invention is such that the two threads incident to any given replenishing operation become disconnected from the thread cutter and clamp and are drawn into their respective pneumatic devices before the next pair of threads incident to the following replenishing operation comes under control of the thread cutter and clamp. For this reason there is no opportunity for entanglement of threads of one transfer with those of another and the mechanism keeps itself clear of weft ends.

The outgoing thread is ordinarily one pick ahead of the incoming thread in the fabric and is likely to be cut by the selvage cutter one pick before the incoming thread is cut. The outgoing thread extends to the lower part of the thread cutter and clamp mechanism and, being cut first, falls out of the path of the descending incoming thread when the latter is cut at the selvage. This relationship is attained by having the thread clamp for the outgoing thread below the hook for the incoming thread, and as a result of this relationship each thread has opportunity to enter the pneumatic thread remover without being interfered with by the other thread.

With these and other objects in view which will appear as the description proceeds, my invention resides in the combination and arrange-

ment of parts hereinafter described and set forth.

In the accompanying drawings, wherein a convenient embodiment of my invention is set forth,

Fig. 1 is a side elevation partly in section showing a loom having my invention applied thereto,

Fig. 2 is an enlarged side elevation as viewed from the center of the loom and showing the thread cutters, clamp, and pneumatic thread remover adjacent to the shuttle feeler, the lay and part of the loom frame being shown in section,

Fig. 3 is an enlarged view of the lower part of the cutter and clamp mechanism showing the parts thereon in normal position,

Fig. 4 is a rear elevation looking in the direction of arrow 4, Fig. 3,

Fig. 5 is an enlarged vertical section on line 5-5, Fig. 3,

Fig. 6 is a view similar to Fig. 3 but showing the cutter and clamp mechanism moved to shuttle detecting position and indicating the primary cutter and thread clamp in open position and the auxiliary cutter in closed position,

Fig. 7 is an enlarged detail front elevation of the pneumatic device looking in the direction of arrow 7, Fig. 2,

Fig. 8 is a detailed plan view looking in the direction of arrow 8, Fig. 7, and

Figs. 9 to 20 are diagrammatic views indicating successive operations of the various parts of the invention and extending over a period including two replenishing operations.

Referring particularly to Figs. 1 and 2, I have shown a loom frame 10 and a lay 11 which is reciprocated in usual manner by the top shaft 12. The loom is provided with a magazine M which in the present instance is preferably of the well-known stationary type to accommodate plural vertical stacks of reserve bobbins from which weft ends W extend to a pneumatic thread holder H. The latter is associated with a thread accumulator 13 supplied with partial vacuum by a pump 14 fixed to the loom frame and having a piston 15 operated by a lever 16 connected to the lay by a rod 17. When the lay moves rearwardly the piston 15 creates a partial vacuum in the front part of the pump 14 and by means of a hose or pipe 18 a partial vacuum is created in the thread collector or accumulator 13 and also in the thread holder H.

Transfer of a bobbin from the magazine into the shuttle S in shuttle box 19 is effected by means commonly employed in stationary magazine weft replenishing looms and including a transerrer arm 20 provided with a latch 21 which can be lifted by mechanism not shown but well understood into the path of a bunter 22 on the lay 11 on those forward beats of the lay when replenishment or transfer occurs.

Many stationary magazines which have gone into use employ a form of shuttle position detector or shuttle feeler designated generally at 25. This feeler moves pivotally around a stationary stud 26 and is positioned by an upwardly extending rod 27 controlled by mechanism not shown, see Fig. 2. Ordinarily, the rod 27 is in down position so that the head 28 at the lower part of the shuttle feeler 25 is in the forward position indicated in Fig. 2. When a replenishing operation is called the head is moved rearwardly by upward movement of rod 27 while the lay is in rear position. If the shuttle S is properly positioned for a transfer it will miss head 28 as the lay approaches front center and the head will be engaged by the shuttle box back or some 75

other part of the lay designated at 29 to be moved to the position shown in Fig. 2. If the shuttle should not be properly positioned for transfer it will engage the head 28 and move the latter forwardly to its normal position at a somewhat earlier time in the cycle of the loom, and in doing so will prevent transfer in well-known manner.

The head 28 supports a horizontal stud 30 held in fixed position on the shuttle feeler by a nut 31, see Figs. 4 and 5. The head is provided with a fixed cutter plate or blade 32 and a movable cutter member 33 pivoted on stud 30. A primary thread clamp 34 is adjacent to the pivoted cutter member 33 and is held against angular movement on the head by the stud 30 and a pin 35 on the head 28. An auxiliary clamp 36 is held against the primary clamp by a leaf spring 37 secured to the shuttle feeler and is pivoted on a sleeve 38 slideable on stud 30 and urged to the left as viewed in Fig. 5 by a compression spring 39. The sleeve 38 extends through the clamps and forces the pivoted or movable cutter member 33 against the fixed blade 32.

The movable member 33 has a forward extension 40 and the auxiliary clamp similarly has a forward extension 41, and both of these extensions are pivoted at 42 to the lower end of an ascending rod 43 the upper end of which is held by a stationary part of the magazine, such as the stand 44 for the stud 26.

When the shuttle feeler is in forward normal position the primary or usual cutter blade 45 of member 33 is in raised or closed position between the fixed cutter blade 32 and the primary clamp 34, and the rear part 46 of the auxiliary clamp is also in closed position in engagement with the right hand surface of the primary clamp 34 as viewed in Fig. 5. When the shuttle feeler moves rearwardly upon call for a replenishing operation the rod 43 acts to cause pivotal movement of the cutter member 33 to swing blade 45 and clamp end 46 downwardly to the open position shown in Fig. 6. Under these conditions the shuttle feeler is in shuttle detecting position and as the lay advances the outgoing thread OT of the outgoing bobbin, see Fig. 10, will enter the notch above the cutter blade 45, provided the shuttle is properly positioned for transfer. Upon return of the head 28 to its normal forward position as the lay beats up rod 43 will cause the cutter blade 45 to rise and cut the thread OT and at the same time force against the clamp 34 that part CT of the thread OT extending between the head 28 and the selvage of the fabric F. Clamped thread CT now extends from the head 28 to the selvage and at some later beatup it will be cut at the selvage by the selvage cutter SC and hang down from the clamps. On the next call for transfer the clamps will open to release thread CT.

That part of the mechanism thus far described may be similar to mechanism heretofore used or shown in my copending application Serial No. 652,405, filed March 6, 1946, now Patent No. 2,446,444. Shuttle feeler cutter mechanisms such as shown in detail in Figs. 3 to 6 are not ordinarily used with pneumatic thread removing devices and because of this fact the clamped part CT of thread OT is not satisfactorily controlled after release and may fall on the lay and be drawn into the warp shed.

In carrying my present invention into effect I provide pneumatic means located under the shuttle feeler head 28 for the purpose of attracting the thread CT. The pneumatic device or remover R is in the present instance mounted on

the front part of the lay, but I do not wish necessarily to be limited to this location. As shown more particularly in Figs. 2, 7 and 8 I provide a support 50 bolted as at 51 to the upper front part of the lay and preferably bend this support forwardly so that the part thereof under head 28 will be spaced forwardly from the lay. Secured to the support 50 is a downwardly extending tube 52 the upper end of which is formed with a guide head 53 secured in any approved manner to support 50 and having in the upper part thereof a V-shaped notch 54 opening upwardly and communicating at its lower end with the interior of the tube 52. This notch is in effect an intake mouth and is preferably under the clamps of the head 28 and extends backwardly and forwardly to receive the thread CT hanging down from the clamps as the lay reciprocates.

The tube 52 is attached to a hose 55 which extends downwardly from the support 50 and then upwardly to communicate with the interior of the thread collector or accumulator 13. From this construction it will be understood that whenever partial vacuum is created within the thread collector during backward movement of the piston 15 there will be an inrush of air through the V-shaped mouth 54 into the tube 52.

After the thread CT has been cut at the selvage as will be described hereinafter and while still clamped by the head 28 it will be drawn pneumatically into the tube 52 due to back and forth motion of this tube between the full and the dotted line positions shown in Fig. 2. When the lay is in rear position the thread CT will extend rearwardly from the clamp into the mouth, but as the lay moves forwardly to the dotted line position in Fig. 2 the thread will extend forwardly from the clamps. The thread will remain in the tube 52 until the next transfer is called, at which time it is released by the clamps and will be sucked through the tube 52 and along the hose 55 into the thread collector 13.

In order to control the incoming thread IT attached to the bobbin 56 which is transferred into shuttle S I provide hook means partly on the lay and partly on head 28. Accordingly, a hook 60 extending upwardly from a part of the shuttle box 19 is positioned for engagement with the incoming thread IT on the next beatup after transfer and is effective to move it over a forwardly facing hook 61 on the upper part of head 28. The movable cutter member 33 has an auxiliary or secondary cutter blade 62 above blade 45 to cooperate with a cutting edge 63 on the upper part of the fixed cutter plate or blade 32. This last named cutting edge and the auxiliary blade are additions to the usual thread cutter mechanism customarily found on the head 28. Blade 62 is normally in the open position shown in Figs. 2 and 3 to form a thread receiving notch 64 with plate 32 when the head 28 is in its normal forward position, and the thread IT will lie under the auxiliary cutter blade 62 and forward of hook 61.

On the first beatup of the lay after transfer hook 60 on the lay moves the thread IT forwardly and over hook 61 to the position shown in Fig. 3 under the auxiliary cutter blade 62. At this time threads CT and IT both extend from the head 28 to the selvage, thread CT being one pick ahead of thread IT at the selvage and being also under the thread IT at the head 28.

As weaving continues forward movement of the fabric will bring the threads CT and IT successively within the range of operations of the selvage

cutter SC and these threads will be cut in the order named. When cut at the selvage thread CT will fall to a position directly under the head but will be attached to the latter by the clamps, and as the intake mouth 54 swings back and forth the lower end of thread CT will be drawn into the tube 52. That end of thread IT adjacent to the fabric when cut at the selvage will also fall from the head toward the reciprocating intake mouth 54 and will be drawn into the tube 52.

It may be that instead of being cut on successive forward beats of the lay, the threads CT and IT will be cut simultaneously, in which event they will fall together to a position where they can enter the mouth 54. Due to the fact, however, that thread CT is attached to the selvage at a point in front of the point of attachment of thread IT it will be cut at a time no later than the cutting of thread IT and for this reason the thread CT will never be taut and extending across the path of the downwardly falling thread IT to interfere with its movement toward the path traversed by the mouth 54.

These two threads will remain in tube 52 but will be supported by the head 28 until in the continued operation of the loom another replenishing operation is called. At this time the head will be moved rearwardly, thread CT will be released as already described and thread IT will be cut by the blade 62. These threads will then be drawn into the tube by the subatmospheric pressures existing therein. It will be understood that when the head 28 moves forwardly from its shuttle detecting position to normal position the blade 62 will be moved to open position and thread IT from the incoming bobbin will not be pushed over the hook 61 until the next beatup. Blade 62 is therefore always raised to receive a thread IT when the latter moves over hook 61.

Certain operations of the pneumatic remover and thread holder, the clamps, and the cutter blades covering a span of two replenishing operations are shown diagrammatically in Figs. 9 to 20. In Fig. 9 the shuttle is shown as moving toward the magazine end of the loom where it is destined for replenishment, a condition requiring that the head 28 be in rear position while the lay is still behind the fell. In Fig. 10 the shuttle is boxed and its thread OT extends from the cloth to the shuttle, the lay moving forwardly and being approximately on bottom center position. In Fig. 11 the lay is near front center and the head 28 has been moved forwardly by the lay to cut the thread OT and clamp the part CT thereof. Fig. 12 shows the lay on front center with the ejected bobbin B being discharged from the shuttle and carrying with it that part of thread OT to the right of head 28. The latter has by this time been returned to its forward position. Fig. 13 suggests a condition occurring closely following the conditions indicated at Fig. 12 with the thread IT of the incoming bobbin extending from the thread holder H into the shuttle. Fig. 14 indicates the position of the lay at the time of picking and suggests that the incoming thread IT lies behind the head 28. Fig. 15 indicates the next front center position of the lay with hook 60 placing the thread IT over the hook 61 and under the auxiliary cutter blade 62.

The condition of the threads shown in Fig. 15 continues for several beats, during which the fabric moves forwardly. In Fig. 16 it is assumed that the lay has just passed its front center position and selvage cutter SC has cut the thread CT and the latter has been drawn into tube 52

but is still attached to the clamp. Fig. 17 is two picks after Fig. 16 and the left end of thread IT has been cut at the selvage and drawn into tube 52. The thread conditions shown in Fig. 17 continue for a number of picks until the next transfer, thread CT being clamped and thread IT not yet cut by blade 62. The partial vacuum existing in the tube 52 will hold these threads taut, but will not be able to remove them.

Fig. 18 sets forth the conditions incident to the next call for transfer occurring several picks after Fig. 17. As the head 28 moves rearwardly again for the next replenishing operation while the lay is advancing thread CT is unclamped and thread IT is cut by blade 62. Both of these threads are still in tube 52. In Fig. 19, the lay is shown at front center and conditions for the new outgoing and incoming threads will be similar to those shown in Fig. 12. As the lay moves rearwardly as in Fig. 20 the partial vacuum in tube 52 removes the threads in it, and the thread holder H removes the right hand part of thread IT. The threads of one transfer are therefore effectively removed before they can become entangled with threads of the following transfer.

From the foregoing it will be seen that I have provided means for clamping part of the outgoing thread long enough to permit cutting at the selvage and subsequent entry into the thread remover. The incoming thread is retained by a hook under an auxiliary cutter which will ordinarily operate subsequent to selvage cutting and after the free end of the incoming thread has had an opportunity to enter the pneumatic thread remover. The mechanism operates in such manner as to clear itself of the threads incident to any given transfer before acting on the threads of the next transfer. Furthermore, the thread first to be cut at the selvage leads to the lower part of the thread cutter and clamp and falls toward the pneumatic thread remover before the incoming thread is cut at the selvage. By this order of operation and relation of threads the lower thread falls to a non-interfering position before the upper thread is cut. Both the outgoing and the incoming threads will ordinarily be cut at the selvage and have an opportunity to enter the pneumatic thread remover before they are released by the thread cutter and clamp. Also, the auxiliary cutter blade is open on forward movement of the head 28 incident to a transfer and is therefore in position to receive the incoming thread incident to that transfer on the next beatup of the lay.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a lay along which a thread extends from a depleted shuttle to the adjacent selvage, cutter and clamp mechanism between the selvage and shuttle effective to cut said thread and clamp the part thereof extending from the mechanism to the selvage, a selvage cutter effective to sever said part of the thread at the selvage subsequent to clamping thereof, whereupon said part of the thread depends from the cutter and clamp mechanism, and a pneumatic thread remover on the lay traversing a path below said cutter and clamp mechanism and into which the lower end of said part of the thread is drawn pneumatically subsequent to cutting at the selvage while still held by said mech-

anism, the latter subsequently releasing said part of the thread and the latter then being drawn into said pneumatic remover.

2. In a weft replenishing loom having a lay along which a thread extends from a depleted shuttle to the adjacent selvage, cutter and clamp mechanism normally in closed forward position, said mechanism moving rearwardly and opening to receive said thread incident to a replenishing operation of the loom and then returning to closed forward position to cut said thread and clamp that part thereof extending from the mechanism to the selvage, means operative subsequent to said forward movement of said mechanism to cut said part of the thread at the selvage, whereupon the thread hangs from said clamp, and a pneumatic thread remover in which subatmospheric pressures exist on the lay traversing a path under said mechanism and operative due to motion thereof and the subatmospheric pressures therein to effect entry of the lower end of said part of the thread thereinto while said thread is still clamped by the mechanism, said mechanism upon a subsequent rearward movement thereof releasing said thread and the latter thereupon being drawn into said pneumatic thread remover.

3. In a weft replenishing loom in which a thread extends from a depleted shuttle to the adjacent cloth selvage, cutter and clamp mechanism intermediate the shuttle and selvage effective on a replenishing operation of the loom to cut the thread between the shuttle and the selvage and clamp that part thereof extending from said mechanism to the selvage, means subsequently cutting said part of the thread at the selvage while said part is clamped by the mechanism and said part of the thread thereafter hanging from said mechanism, a pneumatic thread remover under said mechanism, and means causing said pneumatic remover to traverse a path adjacent to the lower end of said part of the thread, said remover drawing the lower end of said part of the thread thereinto while the upper end of said part of the thread is clamped, and said mechanism subsequently unclamping the upper part of said thread.

4. In a weft replenishing loom in which a thread extends from a depleted shuttle to the adjacent cloth selvage, cutter and clamp mechanism normally closed and in forward position and effective incident to a replenishing operation of the loom to move rearwardly to open position to receive said thread and then move forwardly to cut said thread and clamp that part thereof extending to the selvage, means to cut said part at the selvage subsequent to said forward movement of the mechanism, said part of the thread thereupon depending from said clamp, and a pneumatic thread remover moving in a path adjacent to the lower end of said part of the thread and effective to draw said lower end thereinto while the upper end of said part of the thread is still clamped, said mechanism upon the next transferring operation of the loom moving rearwardly to release said part of the thread and said remover thereupon drawing said part of the thread thereinto.

5. In a weft replenishing loom in which a thread extends from a depleted shuttle to the adjacent cloth selvage, the loom having provision for cutting said thread at the selvage, clamping means to clamp part of the thread extending from the selvage prior to cutting thereof at the selvage, the thread depending from said clamp

subsequent to cutting thereof at the selvage, and pneumatic means below said clamping means to cause entry thereinto by suction of the lower end of said part of the thread while the upper end of the latter is clamped, said clamp subsequently releasing the thread and the pneumatic remover thereupon drawing said part of the thread thereinto.

6. In a weft replenishing loom in which a thread extends from a depleted shuttle to the adjacent cloth selvage, the loom having provision for cutting said thread at the selvage, clamping means to clamp part of the thread between said clamping means and the selvage prior to cutting at the selvage and effective to support said part of the thread subsequent to cutting at the selvage, said part of the thread depending from the clamp means, and a pneumatic thread remover moving relatively to the clamping means along a path below said clamping means and in position to attract thereinto the lower end of said part of the thread while the upper end thereof is still held by said clamping means, the latter eventually releasing said upper end by said part of the thread and the latter thereupon being drawn into said pneumatic remover.

7. In a weft replenishing loom having a pneumatic thread holder from which a thread extends to the adjacent selvage subsequent to a replenishing operation of the loom, means to support said thread at a point intermediate the thread holder and the selvage, means to cut said thread at the selvage, whereupon that part of said thread between said point and said selvage depends from said supporting means, a pneumatic thread remover under said supporting means into which that part of the thread severed from the selvage is drawn, and means thereafter to cut said thread at said point, whereupon that part of the thread between said point and said remover is drawn into the latter and that part of the thread between said point and said thread holder is subject to an attractive force exerted by the thread holder.

8. In a weft replenishing loom having a thread holder from which a thread extends to the adjacent selvage subsequent to a replenishing operation of the loom, supporting means to support said thread at a point between the thread holder and selvage, a pneumatic thread remover below said supporting means, means to cut said thread at the selvage, whereupon that part of said thread cut from the selvage depends from said supporting means and is attracted into said pneumatic remover, and subsequently acting means to cut said thread at a point adjacent to said supporting means.

9. In a weft replenishing loom having a thread holder from which a thread extends to the adjacent selvage subsequent to a replenishing operation of the loom, supporting means for said thread engaging the latter at a point intermediate the thread holder and the selvage, a pneumatic thread remover under said supporting means, means to cause reciprocation of said remover along a path below said supporting means, means to cut said thread at the selvage, whereupon that part of said thread cut from the selvage falls toward said path and is drawn into said pneumatic remover while the thread is still supported by said supporting means, and subsequently acting means to cut said thread at a point therealong between the thread holder and said pneumatic remover, whereupon that part of the thread extending

from said point to said remover will be drawn into the latter.

10. In a weft replenishing loom having a reciprocating lay and having a thread adjacent to said lay extending from a pneumatic thread holder to the cloth selvage, a pneumatic thread holder mounted on and reciprocating backwardly and forwardly with the lay, supporting means above said remover to engage and support said thread between the thread holder and the selvage, means to cut said thread at the selvage, whereupon that part of the thread cut from the selvage hangs downwardly from said supporting means adjacent to said remover and is drawn into the latter, and subsequently acting means to cut said thread along the length thereof at a point between the thread holder and the remover, whereupon that part of the thread between said point and remover is drawn into the latter and that part of the thread between said point and the thread holder is drawn into said thread holder.

11. In a weft replenishing loom having a thread corresponding to an outgoing bobbin attached to the selvage at a point in front of a second thread corresponding to an incoming bobbin and also attached to the cloth selvage, cutter and clamp mechanism to the lower part of which the first named thread is clamped and on the upper part of which the second thread is supported, a pneumatic thread remover under said mechanism, means to cut the first named thread at the selvage and thereafter cut said second thread at the selvage as said threads move forwardly with the cloth, the first thread when cut at the selvage falling while clamped by said mechanism toward said remover at a given time and the second thread when cut at said selvage at a later time falling toward said remover.

12. In a cutter and clamp mechanism for two threads extending from the selvage of the cloth in a weft replenishing loom, one of said threads corresponding to the outgoing bobbin and the other thread above said one thread and corresponding to the incoming bobbin incident to a replenishing operation of the loom, said mechanism having cutting and clamping means for said one thread movable in one direction relatively to said mechanism to cut and clamp said one thread, and said mechanism having a second cutter moving with and above said cutting and clamping means to cut said other thread when said cutting and clamping means moves oppositely to said one direction.

13. In cutter and clamp mechanism for two threads extending from the selvage of the cloth in a weft replenishing loom, one of said threads corresponding to the outgoing bobbin and the other thread above said one thread and corresponding to the incoming bobbin incident to a replenishing operation of the loom, said mechanism having cutting and clamping means for said one thread movable relatively to said mechanism to cut and clamp said one thread, and said mechanism having a second cutter above said cutting and clamping means to cut said other thread, and a hook on said mechanism to position said other thread for cutting by said second cutter.

14. In thread cutter and clamping mechanism for two vertically spaced threads in a loom, cutter and clamp means movable in one direction with respect to the mechanism for action on the lower one of said threads, and an auxiliary cutter moving with and located above said cutter and clamp

11

means and movable in the opposite direction with respect to the mechanism for cutting the upper one of said threads.

15. In thread cutting and clamping mechanism for two vertically spaced threads in a weft replenishing loom, movable cutter and clamp means mounted on said mechanism to cut and clamp the lower one of said threads, an auxiliary cutter connected to said means and movable therewith on said mechanism to cut the upper one of said threads, and a hook on said mechanism to hold the upper one of said threads in cutting position with respect to said auxiliary cutter.

16. In thread cutting and clamping means for two vertically spaced threads of a weft replenishing loom, said mechanism including a head, a cutter having primary and auxiliary cutter blades, one below the other, mounted on the head for movement relatively thereto in opposite directions, and a cutter plate fixed with respect to the head to cooperate with said primary and auxiliary blades, said primary blade effective to sever the lower one of said threads when the blades move in one direction relatively to said head and said auxiliary blade effective to sever the upper one of said threads when the blades move in the opposite direction relatively to said head.

17. In thread cutting and clamping mechanism for two threads of a weft replenishing loom, said mechanism including a head, a cutting member pivotally mounted on the head and having a primary blade and a secondary blade spaced from the primary blade, a cutter plate fixed on said head to cooperate with both of said blades, said plate cooperating with one of said blades to have a cutting operation with respect to one of said threads when said member pivots in one direction relatively to said head, and said plate cooperating with the other of said blades to have a cutting operation with respect to the other of said threads when said member pivots in the opposite direction relatively to said head.

18. In a weft replenishing loom in which successive replenishing beats occur and in which a

thread extends from a thread holder to the selvage on the beat of the loom next following each replenishing beat, normally open cutter means defining a notch to receive said threads, means closing said cutter means on each replenishing beat of the loom and then immediately opening said cutter prior to the beat next following, and means effective on the beat of the loom next following each replenishing beat to move the thread extending between the thread holder and the selvage into said notch.

19. In a weft replenishing loom in which successive replenishing beats occur, and in which a thread extends from a thread holder to the selvage on the beat of the loom next following each replenishing beat, normally open cutter means defining a notch to receive said threads, means closing said cutter on each replenishing beat of the loom and then immediately opening said cutter prior to the beat next following, means effective on the beat of the loom next following each replenishing beat to move the thread extending between the thread holder and the selvage into said notch, and retaining means effective to hold said thread in said notch and in position to be cut by cutting relation with said cutter means.
